RADIO ANTENNA SYSTEM

Howard K. Morgan, Kansas City, Mo., assignor
to Transcontinental & Western Air, Inc.,
Kansas City, Mo., a corporation

Application July 25, 1938, Serial No. 221,087

1 Claim. (Cl. 250—33)

This invention relates to radio antenna systems of the single wire type, particularly to such antennae that are responsive to currents of different, predetermined frequencies, and which are remotely located and wired to a radio receiver or transmitter.

The primary object of this invention is to provide an antenna system of the aforementioned character, the antenna of which is divided into a plurality of sections between which is connected tuned anti-resonant circuits that serve as electrical insulators for currents having frequencies for which the circuits are resonated; that serve to eliminate standing waves on the transmission line feeding or receiving energy from the antenna so that efficient transfer of such energy will automatically occur without the necessity of employing compensating circuits; and that serve as means for presenting a constant 20 impedance from the antenna.

A yet further aim of the present invention is to provide a radio antenna system having a plurality of sections between which are connected resonant, tuned circuits which present high resistance to currents of predetermined frequencies 25 dependent upon the frequency for which the circuits are resonated.

An even further object of the invention is to provide an antenna system having exceptionally great efficiency at each of a number of predetermined current frequencies and including a number of anti-resonant circuits which divide the single antenna into a number of sections to the end that no switching in the antenna circuit nor 35 networks at the antenna feed point are required to tune the antenna to any one of a number of frequencies.

It is understood that heretofore, a number of methods of tuning antennae to predetermined frequencies have been tried. Some of these methods included the step of inserting reactance in the antenna structure, but the efficiency of such methods does not approach that of the present invention, which contemplates the inclusion in 40 the antenna system of a number of resonant tuned circuits which are actually electrical insulators against currents of certain frequencies.

Another of the primary objects of this invention is the provision of an antenna system, which 50 is connected to a remotely located radio receiver or transmitter by a transmission line, having a non-tuned but closely coupled transformer at the point of connection between the two-wire antenna feeder and the concentric transmission line.

A further important object of the invention is the provision of an antenna system having a single wire antenna with a two-wire antenna feeder, which feeder is electrically connected to the transmission line leading to a remotely positioned receiver or transmitter by a transformer between the coils of which is disposed an electrostatic shield for the purpose of preventing any vertically polarized disturbance, or other radiation, from being conveyed down the concentric 5 line with the signal. This said shield is used to a greater advantage with radio receivers than with radio transmitters, but its presence does not lower the efficiency in the antenna system and therefore, it is desirable to include the shield 10 whenever the aforesaid transformer is used as a means for connecting the antenna feeder or lead to a concentric transmission line.

A yet further aim of the present invention is to provide an antenna system having a number 20 of anti-resonant circuits which establish a definite predetermined amount of anti-resonant impedance so that the point of feed (point of connection between antenna and feed line), may be adjusted in resistance within reasonable limits for the most efficient transfer of energy to the transmission line.

Specific objects and methods of employing the invention in an antenna system, will appear during the course of the following specification, referring to the accompanying drawing wherein:

Figure 1 is a schematic circuit diagram illustrating one embodiment of the invention.

Fig. 2 is a circuit diagram of another embodiment of the invention illustrating the use of a 35 transformer.

Fig. 3 is a schematic circuit diagram, similar to Fig. 1, but illustrating an antenna provided for four frequencies; and

Fig. 4 is a schematic illustration of a portion 40 of an antenna system, showing the invention as applied to vertical grounded antennae.

The antenna system diagrammatically illustrated in Fig. 1, is constructed for use when two frequencies are employed and the proper choice 45 of the antenna 6 and tuned circuits 8 and 10, insures that the system will automatically operate at the two frequencies as regards the radio receiver and transmitter, not here shown, and which are located at a remote point and connected to the same by transmission wires 12 and 14 that are joined to the two-wire antenna feeder 16.

Antenna 6 is a single antenna disposed in a horizontal plane and the doublet is tuned to two 55

5 frequencies, one of which is one half an electrical wave length. The section of antenna 6 designated A—B between circuits 8 and 10, is responsive to the predetermined frequency of one half wave length. Circuits 8 and 10 are carefully tuned to this frequency so that they act as electrical insulators and prevent the flow of radio frequency energy from section A—B to wires beyond the ends of said section where circuits 10 8 and 10 are connected.

At another longer wave length and frequency, the length of antenna C—D is one half an electrical wave length.

15 The antenna illustrated in Fig. 2 is in part precisely the same as that shown in the schematic circuit diagram of Fig. 1. Tuned circuits 8 and 10 are the same and sections A—B and C—D are similar. The antenna feeder wires 16, however, are joined to one coil 18 of a closely coupled 20 transformer 20, while the other coil 22 thereof is joined to the concentric transmission line 24 leading to a receiver or transmitter located at some remote point.

25 An electrostatic screen shield 26 is interposed between the primary and secondary coils of transformer 20 for the purpose of preventing any vertically polarized disturbance or radiation from being passed down the concentric transmission lines 24 with the signal. In view of this particular function of the electrostatic screen shield, it will be obvious that it is a valuable element in the system when the antenna is being used as a part of a radio receiver.

30 The antennae illustrated in Figs. 1 and 2 as hereinabove described, are tuned to two frequencies and to indicate the value of the invention, Fig. 3 has been shown in the drawing as an illustration of the manner in which four frequencies are involved.

40 Tuned circuits 28, 30 and 32, on one side of the double feeder lines 34, and tuned circuits 36, 38 and 40 on the other side of the feeder lines 34, serve as electrical insulators for the currents having frequencies for which the circuits just 45 enumerated, are resonated. The impedance thus afforded is practically constant and resistive in the case of each frequency where the transmission line 42 joins the feeder lines 34. In this instance, section E—F is tuned to the highest 50 frequency, section G—H is tuned to the next lowest frequency, section J—K is tuned to the next frequency below the last mentioned, and section L—M is tuned to the very lowest frequency to which the antenna is responsive.

55 Quarter wave tuned sections cannot be substituted for the anti-resonant circuits above mentioned. If such quarter wave sections were used, a coupling of energy to sections beyond the position of the tuned circuit, would occur and this is

not desirable. This invention, however, applies to other than horizontal doublets and multi-section antennae of half wave lengths. Quarter wave grounded antennae of the vertical type, as schematically disclosed in Fig. 4, may be made to embody the invention. Tuned circuits 44, 46 and 48 are interposed in the antenna 50, which is connected to a remotely positioned receiver or transmitter by transmission lines 52, one of which is grounded.

10 All of the resonant tuned circuits heretofore designated by numerals and described as being interposed in an antenna, comprise an inductor 54 and a capacitor 56 (Fig. 1).

Raising the impedance of the anti-resonant 15 circuits will result in lowering the impedance to the transmission line while lowering the impedance of the anti-resonant circuits will result in raising the impedance to the transmission line. The circuits adjacent to the point of feed 58 20 may be adjusted when setting the system for use so as to raise or lower the impedance at those points.

It will be obvious to one skilled in the art that antenna systems made as illustrated and described, will be capable of fulfilling the objects as set down herein, and a remotely operated antenna may have a substantially constant impedance established therein when constructed as disclosed.

30 Having thus described the invention, what is claimed as new and desired to be secured by Letters Patent is:

In a radio antenna system of the doublet type, a transmission line adapted to be connected to a 35 receiver or a transmitter, said antenna comprising a short wave doublet section and a long wave doublet section, the short wave section having a length equal to the length of a half wave of the higher frequency to be received, a pair of 40 down-lead conductors connected to the mid point of the short wave section and in series therewith, an anti-resonant tank circuit tuned to said frequency connected at one end thereof to each end of the short wave section, an antenna section 45 connected to the other end of each tank circuit and forming with said first-named section a long wave doublet section, the last-named section corresponding in length to that of a half wave length of a lower frequency to be received, a non-tuned 50 closely coupled transformer having one coil thereof connected to the lower ends of said down-lead conductors, a hollow cylindrical conductor and a conductor passing therethrough, the other coil of said transformer having its terminals connected, respectively, to said last-named conductors.

HOWARD K. MORGAN.
